His Attorney.

UNITED STATES PATENT OFFICE

ROBERT H. COLLINGHAM, OF RUGBY, ENGLAND, ASSIGNOR TO GENERAL ELECTRIC COMPANY, A CORPORATION OF NEW YORK

ELASTIC FLUID TURBINE

Application filed March 25, 1927, Serial No. 178,455, and in Great Britain April 27, 1926.

The present invention relates to elastic fluid turbines and more particularly to high-powered turbines designed to give a large output, although not limited thereto. High-powered turbines as hitherto constructed have been divided into separate high pressure and low pressure units arranged side by side each unit being directly coupled to an alternating current generator and the separate alternators being electrically connected or interlocked. The elastic fluid ends of the units are connected together by piping and in such machines there is always a considerable drop in pressure between the casings.

One object of the present invention is to provide an improved construction and arrangement in a turbine of the above referred to type wherein the pressure drop between the respective casings of the turbine is eliminated or at least decreased to a considerable extent so as thereby to increase the efficiency of the installation.

A further object of the invention is to provide an improved construction which obviates to a considerable extent expansion troubles.

A further object of the invention is to provide an improved construction and arrangement which may be constructed at comparatively low cost and which is compact so that it is economical of floor space.

For a consideration of what I believe to be novel and my invention, attention is directed to the accompanying description and the claims appended thereto.

In the drawing, Fig. 1 is a plan view of a diagrammatic character illustrating an arrangement embodying the invention, and Fig. 2 is an elevation looking toward the admission end of one of the lower pressure turbine units.

Referring to the drawing, 1 represents the rotor of the high pressure turbine contained in the casing 2. The shaft 3 of rotor 1 is carried in suitable bearings and is connected by a suitable coupling to the rotor of an alternator 4. 5 and 6 indicate the rotors of lower pressure turbines contained in casings 7 and 8 respectively.

The exhaust end of the high pressure turbine is formed by the inlet ends of the casings 7 and 8 of the two lower pressure turbines which turbines receive the exhaust in parallel from the high pressure turbine. The structure forming the exhaust end of the high pressure turbine and the inlet ends of the low pressure turbines is indicated at 9. It comprises an annular chamber 10 which merges directly into two annular chambers 11, chambers 10 and 11 being connected by passages 12, between which the elastic fluid is divided. 13 indicates strengthening webs in passages 12. Passages 12 are shaped to convey the elastic fluid from chamber 10 to the chambers 11 with minimum drop in pressure. In this connection it will be noted that the passages are comparatively short and receive the elastic fluid from around the entire circumference of the annular chamber 10. The two passages may be, with advantage, substantially U-shaped.

The rotors 5 and 6 of the low pressure turbines may be mounted on separate shafts and arranged to be coupled to separate alternators or they may be connected together and drive a single alternator. In the present instance, the latter arrangement is shown, the two shafts being connected together by a coupling as indicated at 14, both rotors driving the alternator 15. The exhaust housings 16 of the low pressure turbines are connected directly to suitable condensers 17.

The high pressure turbine has its shaft 3 located at a right angle to the shafts of rotors 5 and 6 of the lower pressure turbines. This arrangement is of substantial advantage in that it enables the low pressure end of the high pressure turbine to be brought up close to the high pressure ends of the lower pressure turbines so that such ends may merge directly into each other. Also, the arrangement has the advantage that it serves to reduce to a minimum the floor space required by the installation. In this connection, it will be understood that a high pressure turbine such as that indicated in the drawing, in actual practice, becomes relatively small in size particularly where elastic fluid of a pressure higher than those ordinarily in use today is utilized.

Elastic fluid is supplied to the inlet end of

100

the high pressure turbine through a conduit 19 in which is arranged a suitable governing mechanism. The governing mechanism is not illustrated in the drawing since it forms no part of the present invention. It will be understood, however, that it is contemplated to use a suitable governing mechanism such as is provided in connection with turbines of this type. By way of illustration, a simple hand valve 18 is shown as being arranged 10 in conduit 19.

In the exhaust end of the high pressure turbine unit the elastic fluid passes in parallel to the two lower pressure units and after passing through the lower pressure units 15 it is discharged through exhaust conduits 16 to the condenser 17. The high pressure unit and the lower pressure units may rotate at the same speed or they may rotate at complementary speeds, the arrangement being 20 such that the cycles of the alternators driven by them will coincide so that the alternators may be electrically interlocked as is required usually in connection with turbine installations of this type. As one example, the high 25 pressure rotor may rotate at 3000 revolutions per minute and drive a two-pole alternator so as to generate a 50-cycle current while the low pressure rotors may operate at 1500 revolutions per minute and be connected to a 4-pole alternator so that it will deliver also a 30 50-cycle current.

A construction of the above referred type is well adapted to have the elastic fluid re-heated at an intermediate point especially at 35 a point between the higher pressure turbine unit and the two lower pressure units. To this end, I may with advantage provide suitable heating means in connection with the annular chambers 10 and 11 and the passages 40 12. For example, there may be provided in the passages nests of tubes of suitable shape. For example, substantially U-shaped nests of tubes may be arranged in the U-shaped 45 passages 12, and through which a suitable heating medium may be circulated. For example, flue gases may be circulated through such tubes or highly superheated live steam may be circulated through such tubes. In the latter case, the elastic fluid circulated through 50 the nests of tubes may be returned to the boiler or, after circulating through the nests of tubes, it may be admitted directly to the high pressure turbine or to the lower pressure turbines. In Fig. 1, 20 indicates diagrammatically nests of tubes arranged in 55 passages 12.

What I claim as new and desire to secure by Letters Patent of the United States, is:—

1. An elastic fluid turbine comprising a 60 higher pressure unit and two lower pressure units, said lower pressure units being arranged in axial alignment with their admission ends adjacent to each other and said higher pressure unit being arranged at an angle to the lower pressure units and with its

exhaust end adjacent and connected directly to the admission ends of the lower pressure units.

2. An elastic fluid turbine comprising a higher pressure unit and two lower pressure units, said lower pressure units being arranged in axial alignment with their admission ends adjacent to each other and said higher pressure unit being arranged at an angle to the lower pressure units and with its 70 exhaust end adjacent to the admission ends of the lower pressure units, the exhaust end of the higher pressure unit merging into and forming the admission ends of the lower pressure units. 75

3. An elastic fluid turbine comprising a pair of lower pressure units arranged with their fluid receiving ends adjacent and facing each other and their rotors arranged in the same axial plane, a higher pressure unit 80 arranged at an angle to the lower pressure units, and a housing which mechanically unites the exhaust end of the higher pressure unit with the inlets of the two lower pressure units and through which the exhaust fluid from the higher pressure unit flows in multiple to the lower pressure units. 85

4. An elastic fluid turbine comprising a pair of lower pressure units arranged end to end with their inlets facing each other and their rotors arranged in the same axial plane, a higher pressure unit arranged at substantially a right angle thereto, the axis of its rotor being in substantially the same horizontal plane as the axes of the lower pressure units, and a housing comprising an annular member which unites the three units, 90 receives the exhaust from the higher pressure unit and discharges it in multiple to the two lower pressure units. 95

5. An elastic fluid turbine comprising a higher pressure turbine unit and a plurality of lower pressure turbine units arranged in separate casings and with their admission ends adjacent to each other, a housing which is located at the exhaust end of the higher pressure unit, is connected to the inlets of said lower pressure units and contains substantially U-shaped passages which convey 100 exhaust fluid from the unit of higher pressure to the other and exhaust fluid heating means arranged in said U-shaped passages. 110

In witness whereof, I have hereunto set my hand this third day of March, 1927.

ROBERT H. COLLINGHAM.
